(57) **CLAIM**

The ornamental design for a car steering wheel and/or toy replica, as shown and described.

DESCRIPTION

FIG. 1 is a front perspective view of the car steering wheel and/or toy replica showing my design thereof;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the car steering wheel and/or toy replica and form no part of the claimed design.
